J. HAAS, JR.
CURTAIN FASTENER.
APPLICATION FILED AUG. 19, 1911.

1,093,927.

Patented Apr. 21, 1914.

UNITED STATES PATENT OFFICE.

JOSEPH HAAS, JR., OF NEWPORT, KENTUCKY.

CURTAIN-FASTENER.

1,093,927.

Specification of Letters Patent.

Patented Apr. 21, 1914.

Application filed August 19, 1911. Serial No. 645,045.

To all whom it may concern:

Be it known that I, JOSEPH HAAS, Jr., a citizen of the United States, and a resident of the city of Newport, in the county of Campbell and State of Kentucky, have invented certain new and useful Improvements in Curtain-Fasteners, of which the following is a full, clear, and exact description, reference being had to the accompanying drawings, forming part of this specification.

My invention relates to curtain fasteners for securing curtains and the like to framework, and more particularly for use for curtains on vehicles, especially for automobiles, where the curtains are subjected to heavy and violent wind pressure and the fasteners are under almost continuous jarring and jolting strains.

The object of my invention is to provide a curtain fastener of the turn button kind, which shall be strong and durable, and at the same time light and attractive in appearance, and easily operated to release or lock the curtain in position and with which the liability of jarring loose under jolting strains and varying wind pressure will be reduced to a minimum.

The several features of my invention and the various advantages resulting from their use conjointly or otherwise will be apparent from the following description and claims.

In the drawings, Figure 1 is a top plan view of my improved curtain fastener. Fig. 2 is a central transverse section of the same. Fig. 3 is a side elevation of the button stud. Fig. 4 is a plan view of the rotatable locking disk. Fig. 5 is a side elevation of the same. Fig. 6 is a plan view of the bottom plate, and Figs. 7 and 8 are plan and side elevations of the top plates, between which plates the locking disk is mounted. Fig. 9 is a plan view of the clenching plate employed as a base for the attachment of the fastener to the curtain material.

A portion of the frame to which the curtain is to be fastened is represented by 1, and the curtain material by 2. At each point at which the curtain is to be fastened, a post or stud 3 is permanently fixed or secured in any suitable way. In the construction of stud illustrated, 4 is the base of the stud, provided with a depending stem 5 for securing the stud in position. The head of

the stud 6 is provided with lateral extensions 7, 7, formed by undercutting the head portion with a groove 8, and in the preferred construction the head is oblong in 60 shape.

Secured to the curtain material 2, at the proper points for fastening to the studs, are the turn button fasteners. The turn button comprises a disk 9, preferably of resilient sheet metal, provided with an opening 10, corresponding in size and shape to the head 6 of the stud, so as to allow for the passage of the head when the disk is in one position, and so that the side edges of 70 the disk will engage under the lateral extensions of the head when the disk is given a quarter turn. The locking disk is provided with a suitable finger hold 11, extending upwardly from the plate to be readily 75 grasped, and in the present instance this finger hold comprises a semi-circular loop of wire secured at its ends to the disk. The disk 9 is mounted on a bottom plate 12, provided with a similar opening 13 to that 80 in the locking disk, and the locking disk is held in place by the annular top plate 14, which is provided with tangs 15, 15, to pass down through slots 16, 16, in the bottom plate and through the curtain material 2 85 and through slots 17, 17, in the annular clenching plate 18, which is placed on the under surface of the curtain material, and over which the tangs 15 are clenched to secure the fastener to the curtain material. 90

The locking disk 9 is bent slightly transversely as illustrated in Fig. 5, so as to give resiliency to the disk, and lugs 19, 19, are formed on the under surface of the locking disk by depressing the material at these 95 points, while the bottom plate 12 is provided with corresponding depressions 20 arranged ninety degrees apart, in line with the major and minor axes of the oval opening 13, so that in either of the two positions of the 100 locking disk the spring of the plate will cause the lugs to engage in the depressions and lock the disk in open or closed position.

The use of the curtain fastener will be evident from the foregoing description. To 105 secure the curtain, the locking plate 9 is turned so that the oval opening 10 will be parallel with the head of the stud; the head of the stud is then passed through the oval opening and the locking plate given a 110 quarter of a turn by the finger hold 11, thus bringing the edges of the plate under the

undercut portion of the head of the stud. The resiliency of the plate causes the lugs 19 to engage in the depressions in the bottom plate in either of these two positions to snap in place when the plate is turned, thus locking the plate against any movement under the jars and jolts of the vehicle.

The construction is light and attractive in appearance, is formed of a minimum 10 number of parts, is readily and easily manufactured and can be fastened to the curtain material by merely clenching the tangs 15 over the clenching plate 18.

Having thus described my invention, 15 what I claim as new and desire to secure by Letters Patent, is:—

1. In a curtain fastener, the combination with a fixed button stud having a laterally extending head and adapted to be secured 20 to the frame, of a turn button fastener adapted to be secured to the curtain, comprising an upper and a lower fixed plate with a rotatable plate mounted between the fixed plates, the rotatable plate provided 25 with an opening to allow the passage of the head of the stud when in one position, and to lock under the head of the stud in another position, the rotatable plate formed of resilient sheet metal bent transversely to 30 maintain a spring pressure between the up-

per and lower fixed plates, and provided with raised portions to engage correspondingly depressed portions in the fixed plate to lock the rotatable plate in open and closed positions.

2. In a curtain fastener, the combination with a fixed button stud and adapted to be secured to the frame having a laterally extending head, of a turn button fastener adapted to be secured to the curtain, comprising an upper and a lower fixed plate with a spring plate rotatably mounted between the two fixed plates, said spring plate having an opening to allow the passage of the head of the stud in one position and to 40 lock thereunder in another position, with a finger hold comprising a semi-circular loop extending upwardly from the rotatable plate to rotate the same, the rotatable plate and one of the fixed plates having correspondingly raised and depressed portions to lock the rotatable plate in open and closed positions with said rotatable plate bent transversely to maintain spring pressure between the rotatable plate and the fixed plate. 50 55

JOSEPH HAAS, Jr.
